(57) **CLAIM**

The ornamental design for a movable platform barrier, as shown and described.

DESCRIPTION

FIG. 1. is a perspective view of front, left and top side of a movable platform barrier showing a first embodiment of our new design;

FIG. 2. is a front view thereof;

FIG. 3. is a rear view thereof;

FIG. 4. is a left side thereof;

FIG. 5. is a right side view thereof;

FIG. 6. is a top view thereof; a bottom view is a mirror image thereof;

FIG. 7. is a cross sectional end view of the cross-section 7-7 taken in FIG. 2; and,

FIG. 8. is a reference view of the design in use.

The portions of the article in broken lines are shown for illustrative purposes only and form no part of the claimed design.
